UNITED STATES PATENT OFFICE

164,900

SWIVEL CHAIR BASE

John S. Burdick, North Muskegon, Mich., assignor to The Shaw-Walker Company, Muskegon, Mich., a corporation of Michigan

Original application August 2, 1950, Serial No. 11,544. Divided and this application September 29, 1950, Serial No. 12,405

Term of patent 14 years

(Cl. D15—8)

To all whom it may concern:

Be it known that I, John S. Burdick, a citizen of the United States, residing at North Muskegon, in the county of Muskegon, State of Michigan, have invented a new, original, and ornamental Design for a Swivel Chair Base, of which the following is a specification, reference being made to the accompanying drawing, forming part thereof, wherein:

Figure 1 is a three-quarter perspective view of a swivel chair base showing my new design;

Figure 2 is a side view of a swivel chair base showing my new design; and

Figure 3 is a top plan view of a swivel chair base showing my new design.

The present application is a division of my copending application, Serial Number D. 11,544, filed August 2, 1950.

The design is characterized by the relatively high massive dome-shaped center portion merging into smoothly rounded upper surfaces of the

four legs which sweep downwardly and then outwardly in unbroken tapering lines terminating in upright end surfaces which are generally semi-circular in horizontal section.

I claim:

The ornamental design for a swivel chair base, as shown and described.

JOHN S. BURDICK.
